UNITED STATES PATENT OFFICE.

CHRISTIAN C. HILL, OF CHICAGO, ILLINOIS.

COMPOUND ENGINE.

SPECIFICATION forming part of Letters Patent No. 740,565, dated October 6, 1903.

Application filed October 28, 1901. Serial No. 79,682. (No model.)

To all whom it may concern.

Be it known that I, CHRISTIAN C. HILL, a citizen of the United States of America, and a resident of Chicago, in the county of Cook and State of Illinois, have invented certain new and useful Improvements in Compound Engines, of which the following is a specification.

The present invention relates to compound engines for either pumping or motive-power purposes, and more especially to the oscillating type of such engines.

Various objects of the present improvements are as follows: to provide a simple and efficient controlling-valve mechanism with which the series of individual engine-cylinders comprising the compound engine are adapted to be coupled together in pairs, working compound and attaining a duplex expansion of the motive fluid, or to be coupled in series to attain a quadruple expansion of such motive fluid in case of a motive-power engine and a similar double or quadruple compression of the fluid operated upon in a pumping or compressor engine; also, to provide a simple and efficient construction and arrangement of a single-acting oscillating engine and its individual reversing-valve mechanism with which an efficient reversal of the course of the motive or other fluid is attained and in which the reversing-valve is adapted to act as a relief-valve and in addition is adapted to maintain a steam-tight joint with its seat during continued use and with a minimum amount of friction.

Other and minor objects of the present improvements are to provide means whereby the engine is rendered simple, compact, and durable in construction and efficient and economical in operation, all as will hereinafter more fully appear and be more particularly pointed out in the claims.

I attain such objects by the construction and arrangement of parts illustrated in the accompanying drawings, in which—

Figure 1 is a longitudinal sectional elevation at line $x^2 x^2$, Fig. 2, of a compound engine embodying the present invention; Fig. 2, a transverse sectional elevation of an individual engine at line $x' x'$, Fig. 1, illustrating one position of the engine; Fig. 3, a similar view illustrating another position of said en-

gine; Fig. 4, an enlarged detail longitudinal section at line $x^2 x^2$, Figs. 1 and 8, illustrating the valves and connections of the present invention in position for quadruple expansion; Fig. 5, a similar view of the master-valve and connections, taken at line $x^3 x^3$, Fig. 8; Fig. 6, a transverse section of the same at line $x^4 x^4$, Figs. 5 and 8; Fig. 7, a similar view at line $x^5 x^5$, Figs. 5 and 8; Figs. 8 and 9, vertical longitudinal sections at line $x^6 x^6$, Figs. 5, 6, and 7, illustrating two different portions of the master-valve; Figs. 10 and 11, detail longitudinal sections of the master-valve, similar to Figs. 4 and 5 and illustrating the said valve in position for duplex expansion; Fig. 12, a vertical longitudinal section of the same at line $x^7 x^7$, Fig. 11. Fig. 13 is a longitudinal sectional elevation of a modified form of the master-valve; Figs. 14 and 15, transverse sections of the same at lines $x^8 x^8$ and $x^9 x^9$, respectively.

Similar numerals of reference indicate like parts in the several views.

Referring to the drawings, 1 represents the main frame of the engine, having any usual and suitable form and which will preferably comprise an inclosing casing 2 and a skeleton base or structure provided with bearings for the crank-shaft 3 and the trunnions 4, 4', 4'', and 4''', by which the series of engine-cylinders are supported to oscillate in the main frame.

5' 5'' 5''' are the engine-cylinders, which in the type of compound engines shown in the accompanying drawings as illustrative of the present invention comprise a series of four cylinders having a progressively-increased diameter in manner usual to compound engines. 90 It is, however, within the province of this part of the present invention to increase or diminish the number of engine-cylinders as the particular circumstances or the judgment of the constructor may indicate. Said engine-cylinders are shown as of the single-acting type open at the end adjacent to the crank-shaft and closed at the end removed from such crank-shaft.

6' 6'' 6''' are heads closing the ends of the engine-cylinders removed from the crank-shaft and preferably formed integral with their respective engine-cylinders, as shown. In the present invention each of such closure-

heads will have a convex or segmental face concentric with the axis of oscillation of the engine-cylinders to constitute the oscillating member of the individual reversing-valve, by 5 which the induction and eduction of the motive fluid to each individual engine-cylinder is controlled.

7 7', &c., are individual centrally-arranged ducts or passages in the respective cylinder-heads, which connect with the piston-chambers of the respective engine-cylinders and constitute an induction-eduction duct or passage for each cylinder.

8 8' 8" 8''' are the non-oscillating members 15 of the individual reversing-valves of the respective engine-cylinders, each having a concave or segmental face corresponding with the segmental face of the oscillating valve member above described and adapted to seat 20 thereon, as illustrated more particularly in Figs. 2 and 3.

9 9' 9" 9''' and 10 10' 10" 10''' are counterpart independent ducts or passages in the non-oscillating valve member constituting the 25 induction and eduction passages of the same. Such ducts or passages are of a spiral formation and extend from the respective and opposite ends of each valve member to a pair of ports or openings in the seat or surface of 30 such valve member. Such ports or openings are arranged parallel to each other and transverse to the direction of movement of the oscillating valve member aforesaid and are adapted to alternately register with the single central induction-eduction of the particular engine-cylinder in the oscillation of the 35 same in use.

11 11' 11" 11''' are a series of auxiliary fixed members carried in any suitable manner by 40 the frame of the engine and provided with counterpart independent ducts or passages 12 12' 12" 12''' and 13 13' 13" 13''' identical in formation and arrangement to the ducts or passages 9, &c., and 10, &c., above described 45 and which are respectively in communication in the indirect manner hereinafter described with the main motive-fluid supply and with the main motive-fluid outlet of the engine.

The respective ends of both the aforesaid 50 members 8 8' 8" 8''' and 11 11' 11" 11''' are formed with annular seats of any usual form, preferably the cone or tapering form shown, for connection with correspondingly-formed tubular necks 14 14' 14" 14''' and 15 15' 15" 55 15''' of the hollow counterpart connecting members 16 16' 16" 16''' and 17 17' 17" 17'''.

The said connecting members are adapted to connect the ducts or passages of the respective members 8, &c., and 11, &c., together in 60 an independent manner and as so constructed and arranged constitute a pivotal conducting connection between a stationary member 11 and a non-oscillating valve member 8 to permit of a movement of such valve member to 65 or from its seat upon the cylinder-head, for purposes hereinafter stated.

18 represents a series of tie-bolts connect-

ing the pairs of members 16 and 17, &c., together and tying the parts together in operative relation.

18' represents a series of elastic members inserted between the heads of the bolts 18 and the adjacent surface of the connecting members and adapted to afford a yielding tension to hold the parts in operative engagement.

19 represents a series of elastic compression pieces or members carried by the engine-frame and having an elastic or yielding bearing upon the valve members 8 8', &c., to 80 yieldingly hold the same to their seats upon the heads of the oscillating engine-cylinders to permit said valve members moving away from their seats under undue pressure within such cylinders, and thus constitute a 85 series of independent relief or safety valves for such cylinders in cases where an extraordinary pressure prevails therein. Such provision also maintains a contact of such valve members upon their seats to compensate for wear during continued use of the 90 engine. The said holding member 19 may be of any usual and suitable form and construction adapted to attain the described results. In the construction illustrated in Figs. 95 2 and 3 of the drawings such holding members will each consist of a spring bar or plate attached at one end to the main engine-frame and having intermediate bearing upon the top of the particular valve member, with its other end engaged by a temper-screw and nut 19', by which the tension of such spring-bar is adjusted to suit any particular pressure under which the engine is designed to 100 work.

In the present construction the respective induction and eduction passages or ducts 12, &c., and 13, &c., of the series of auxiliary fixed members 11, &c., of the individual reversing-valve mechanisms will connect 110 with a corresponding series of ducts or passages in the base or seat of the valve chest or casing 20, to be controlled by a master-valve 21, which is adapted in the manner hereinafter described to perform the dual 115 functions of reversing the direction of the revolution of the engine and to control the direction of the motive fluid from engine-cylinder to engine-cylinder, so that the engines may be run compound in pairs with a 120 duplex expansion or in series with a quadruple expansion of the motive fluid.

In the particular type of four-cylinder compound engine shown in the drawings as illustrative of the application of the present invention to a compound engine for power purposes a series of four single-acting engine-cylinders are employed, with a single master-valve controlling the series and having a longitudinal movement upon its seat to change 130 the engine from a quadruple to a duplex expansion arrangement, and vice versa, and a lateral movement to effect a reversal of the direction in which the engine-shaft is rotating.

The valve chest or housing 20 for the master-valve will be of any usual and suitable form, with its seat portion formed with ports and passages, as follows: 22 22' 22" and 23 23' 23" are parallel pairs of ducts or passages extending directly through the base or seat portion of the valve-chest and having communication with the pairs of induction and eduction ducts or passages 12 12' 12" and 13 13' 13" of the auxiliary fixed members 11 11' 11", heretofore described. As shown in the drawings, there are three pairs of such ducts or passages, and each pair individual to the individual reversing-valve mechanisms of the first three of the series of engine-cylinders 5 5' 5". 24 25 are a fourth pair of parallel ducts or passages similarly formed in the base or seat portion of the valve-chest, but differing from the other three pairs of ducts just described in being extended longitudinally through the base of the valve-chest to individually connect with the ducts or passages 12'" and 13'" of the auxiliary fixed member 11'" of the individual reversing-valve mechanism of the fourth or last engine-cylinder of the series. 26 27 are secondary ports or openings in the valve-seat, communicating with the ducts or passages 24 25 immediately back of the forward or main ports or openings of the same for the purposes hereinafter described. 28 28' and 29 29' are parallel pairs of U-shaped longitudinal passages formed in the base or seat portion of the valve-chest and alternating between the first three series of ducts or passages 22 22' 22" and 23 23' 23" aforesaid. Said passages 28 28' 29 29' have ports or openings through the valve-seat in adjacent and longitudinal relation to the passages 22 22', &c., as shown. 30 is an exhaust or outlet duct or passage formed in the base or seat portion of the valve-chest and having a port or opening through the valve-seat. 31 is a receiving-chamber formed in the seat or base portion of the valve-chest and adapted to form, in connection with a chamber in the master-valve, hereinafter described, a receiver for receiving and storing the exhaust motive fluid from a forward engine-cylinder for a given period in the cycle of the engine in which the next engine-cylinder is reaching a position to receive and utilize such motive fluid.

The master-valve 21 will have a hollow trunk form, the interior of which is partitioned off into a smaller exhaust-chamber 32 and a large main storage-chamber 33 to receive the motive fluid from a high-pressure engine-cylinder and store the same until a succeeding low-pressure engine-cylinder comes into proper position to receive and utilize such motive fluid.

The chamber 33 and the chamber 31, before described, are intended to afford sufficient capacity for storing the motive fluid, as above described. When desired, however, the chamber 31 may be enlarged by connection with a closed tank of the desired capacity,

arranged in adjacent relation to the valve-chest 20, as the judgment of the constructor may suggest.

The master-valve will comprise generally a central series of outlet or eduction ducts or passages and two counterpart series of inlet or induction ducts or passages arranged parallel with and at opposite sides of the central series of ducts, the arrangement being such that with a lateral shift of the master-valve in one direction one of said series of inlet-ducts will be brought into active position or communication with the next adjacent series of ducts or openings in the valve-seat, while the counterpart series of said inlet-ducts of the master-valve will be simultaneously shifted to a plane portion of the valve-seat and rendered inoperative, and vice versa, in a lateral movement of the master-valve in the opposite direction. With such lateral movement of the master-valve in either direction the central series of outlet ducts or passages will be shifted in their communication from one to the other of the parallel series of ports or passages 22 22' 22" 24 and 23 23' 23" 25 in the valve-seat to open to eduction the particular series of such ducts which had previous to such movement been in communication with the motive-fluid inlet or induction passages of the engine-cylinders. In detail the aforesaid ducts or passages in the master-valve will comprise a formation and arrangement as follows:

34 represents a counterpart pair of marginally-arranged ducts or passages located at the forward end of the master-valve and each formed with a longitudinal enlargement at its lower end which opens onto the valve-seat, as shown in Figs. 4 and 10. Such passages 34 are open at top and in communication with the interior of the valve-chest 20, in which motive fluid at high pressure prevails, while at bottom one or the other of said ducts are in register with one or the other of the pair of parallel ducts 22 or 23 of the valve-seat, depending upon the lateral position of the master-valve, to supply motive fluid to the first of the series of engines in a constant manner regardless of the longitudinal position of said valve.

In the duplex-expansion position of the master-valve, as illustrated in Figs. 10, 11, and 12, one or the other of the said ducts 34 is adapted to additionally register with and supply high-pressure motive fluid in common to the duct 22 or 23 aforesaid and to the longitudinal passage 28 or 29 in the valve-seat, from whence the motive fluid passes to the second of the series of engine-cylinders, as herein-after more fully described.

35 is a central duct or passage arranged at the forward end of the master-valve and adapted in one longitudinal position of said valve, as illustrated in Figs. 5, 8, and 9, to be closed at its lower end by a plane surface of the valve-seat and remain dormant, while in the other longitudinal position of the master-

valve, as illustrated in Figs. 11 and 12, the said duct or passage 35 is adapted to register the particular duct 22 or 23 through which passes the eduction from the first of the series of engine-cylinders with the receiving or storage chambers 33 of the master-valve, as hereinafter more fully explained in the operation of the invention.

36 36' 36" are a series of branched or V-shaped ducts or passages in the master-valve, the central point of intersection of the branches terminating in centrally-arranged ports or openings 37 37' 37", which are adapted in either of the lateral positions of the master-valve and in the quadruple-expansion position of the same, as illustrated in Figs. 5, 8, and 9, to register with one or the other of the series of ducts 22 22' 22" or 23 23' 23" of the valve-seat and in connection with the same constitute a part of the eduction or exhaust passages for the first three of the series of engine-cylinders when the same are running on quadruple expansion. The respective branches of said passages 36 36' 36" terminate in ports or openings 38 38' 38" in longitudinal alinement with the induction ducts or passages 34 aforesaid and adapted in the above-mentioned position of the master-valve and as illustrated in Figs. 4, 8, and 9 to register with one or the other of the series of longitudinal ducts or passages 28 28' or 29 29' in the valve-seat to conduct the motive fluid from a forward engine-cylinder to the next adjacent engine-cylinder in an operation under quadruple expansion. Said series of branched passages or ducts 36 36' 36" 37 37' 37" 38 38' 38" in the duplex-expansion position of the master-valve, as illustrated in Figs. 10, 11, and 12, assume a dormant or inactive condition.

39 represents a counterpart pair of open-bottomed chambers or passages in the master-valve arranged in longitudinal alinement with the ducts 34 aforesaid and in immediate relation to the ducts or passages 22' 23', which connect with the second engine-cylinder of the series. In the quadruple-expansion position of the master-valve, as illustrated in Figs. 4, 8, and 9, one or the other of said passages 39 is adapted to register the ducts 28 22' or 29 23' together to conduct motive fluid passing away from the first engine-cylinder into the second engine-cylinder for secondary expansion therein, while in the duplex-expansion position of the master-valve, as illustrated in Figs. 10 and 12, one or the other of said passages 39 is adapted to register a high-pressure inlet-duct 34 and intermediate passage 28 or 29 with one or the other of the passages 22' or 23' to introduce high-pressure motive fluid into the second engine-cylinder of the series.

40 represents a counterpart pair of ports or openings in the bottom of the master-valve, arranged in longitudinal alinement with the ducts 34 and 39 aforesaid and in immediate relation to the ducts or passages 22" 23",

which connect with the third engine-cylinder of the series. In the quadruple-expansion position of the master-valve, as illustrated in Figs. 4, 8, and 9, one or the other of said ports 40 is adapted to register the ducts 28' 22" or 29' 23' together through the main storage-chamber 33 of the master-valve to conduct motive fluid passing away from the second engine-cylinder into the third engine-cylinder for tertiary expansion therein, while in the duplex-expansion position of the master-valve, as illustrated in Fig. 10, such ports 40 do not register with the passages 28' or 29', and accordingly such last-mentioned passages remain dormant or inactive.

In the construction shown in the drawings movements of the master-valve in longitudinal and lateral planes are attained by mechanism as follows: 41 is a shaft extending longitudinally through the valve-chest 20 of the master-valve and adapted to have endwise or longitudinal movement as well as a rocking movement therein. 42 is a crank-arm or other usual and equivalent means secured to said shaft outside the valve-chest to afford means for rocking said shaft. 43 is a bell-crank lever or other usual and equivalent means fulcrumed on a stationary portion of the engine, with one of its arms in operative engagement with the shaft 41, to afford means for imparting a longitudinal or endwise movement to said shaft. 44 represents a pair of toothed sectors secured to the shaft 41 within the valve-chest. 45 represents a pair of transversely-arranged toothed racks secured to the master-valve and having operative engagement with the toothed sectors 44, so that with a rocking movement of the shaft 41 in either direction a lateral movement of the master-valve will be effected in a corresponding direction. 46 represents bracket-lugs secured to the top of the master-valve and adapted to abut against the opposed faces of the hubs of the toothed sectors 44 to hold the valve against any independent longitudinal movement with relation to the said toothed sectors and the shaft 41, so that with a longitudinal movement of the shaft in either direction a corresponding longitudinal adjustment of the master-valve will be effected. 47 47', &c., are the pistons of the respective engine-cylinders, which in the construction shown have an annular form and are provided with closure-heads at the ends next adjacent the induction-eduction ducts of the engine-cylinders. 48 represents lugs or projections upon the closure-heads of the pistons, adapted to enter the induction-eduction ducts 6' 6", &c., of the engine-cylinders to effectually displace the motive or other fluid in the back or return strokes of the pistons, and which feature is of especial value where the present invention is employed as a pumping or compressing engine for elastic fluids or gases. 49 49', &c., are the pitman-rods, formed integrally with the pistons and having connection with the annular walls of the pistons by the

integral spiders or arms 50 and with the closure-heads of the pistons by longitudinal extensions, as illustrated in Fig. 1. 51 represents journal-boxes, of any usual construction, carried on the free ends of the pitman-rods 49 and adapted to have operative engagement with the series of crank-arms of the engine-shaft.

In the modified form of the master-valve (illustrated in Figs. 13, 14, and 15) the same arrangement of ducts or passages heretofore described will be maintained, the modification consisting mainly in making such master-valve of a cylindrical form, so that it will have an oscillating movement upon its seat instead of the rectangular lateral movement heretofore described.

Various portions of the present improvements are adapted for effective and economical employment in an engine for pumping or compressing elastic fluids and gases, and it is accordingly within the scope or province of the present invention to so apply the different novel features of the present invention.

25 The operation of the present invention as a motive-power engine will be as follows: With the master-valve 21 in the quadruple-expansion position illustrated in Figs. 2, 3, 4, 5, 6, 7, and 8 of the drawings and with 30 high-pressure motive fluid existing in the interior of the valve-chest 20 of the master-valve the motive fluid will pass from said valve-chest through the marginal duct 34, which is in register with the duct 22, and successively through said duct 22, the duct 12, the passage of the hollow connecting member 16, the duct 9, and the duct 7 into the piston-chamber of the first of the series of engine-cylinders to impart movement to the 40 piston thereof and to the crank-shaft of the engine. As the piston of such engine-cylinder nears the end of its active stroke the individual valve mechanism of such cylinder automatically reverses the position of its ducts 9 and 10, cutting off the communication of the pressure-supply duct 9 with the interior of such engine-cylinder and bringing the eduction-duct 10 into communication therewith. The motive fluid in the first engine-cylinder is now free to expand through the ducts 10, 13, 22, 36, 28, 39, 22', 12', and 9' into the second engine-cylinder to effect an active movement of the piston thereof. As such piston nears the end of its active stroke 55 the individual valve mechanism of such second engine-cylinder automatically reverses the position of its induction and eduction ducts 9' and 10', cutting off the before-described communication with the first engine-cylinder through the duct 9' and its connections and bringing the eduction-duct 108 into communication with the interior of the second engine-cylinder, the motive fluid in which is now free to expand through said duct 108, and the connecting-ducts 13', 23', 36', and 28' 60 into the receiving or storage chamber 33 of the master-valve, wherein such motive fluid

is stored until the third engine-cylinder reaches the proper position to receive such motive fluid. In the present type of compound engines such lag on the part of the third engine-cylinder in reaching such receiving position is due to the quartering position of its crank-arm, as well as the crank-arm of the fourth engine-cylinder, 70 with relation to the crank-arms of the first and second engine-cylinders. Accordingly some means is required for storing the motive fluid during the described interval, and such means is very efficiently provided in 80 the present construction by the receiving-chamber 33 in the master-valve and the secondary receiving-chamber 31 in the base of the valve-casing, &c., as heretofore set forth in the descriptive portion of the specification. 85 With the third engine-cylinder at its receiving position the motive fluid previously stored in the receiving-chamber of the master-valve passes through the ducts 22", 12", 9", and 7" into the piston-chamber of such 90 cylinder to effect an active movement of the piston thereof. As such piston nears the end of its active movement the individual valve mechanism of such third engine-cylinder automatically reverses the position of its induction and eduction ducts 9" and 10", cutting off the before-described communication through duct 9" and its connecting-passages with the chamber 33 of the master-valve and bringing the eduction-duct 10" into communication with the interior of said third engine-cylinder, the motive-fluid of which is now free to expand through said duct 10" and the connecting-ducts 13", 23", 36", 24, 12", and 9" into the fourth engine-cylinder to effect 105 an active movement of the piston thereof. As such piston nears the end of its active movement the individual valve mechanism of such fourth engine-cylinder automatically reverses the position of its induction and eduction ducts 9" and 10", cutting off the before-described communication through the duct 9" and its connecting-passages with the third engine-cylinder and bringing the eduction-duct 10" into communication with the 110 interior of said fourth engine-cylinder, the motive fluid in which is now free to exhaust through the ducts 10", 25, 26, and 32 into the exhaust-outlet passage 30 of the valve-chest and from thence to the atmosphere or 115 to the condenser of the motive-power plant. With the master-valve in the duplex-expansion position illustrated in Figs. 10, 11, and 12 of the drawings and with high-pressure motive fluid existing in the interior of the 120 valve-chest 20 of the master-valve the motive fluid will pass from said valve-chest into the marginal duct 34, which is in direct register with the duct 23 and in indirect register with the duct 23', through ducts or passages 28 39 125 to supply high-pressure motive fluid in common to the first and second engine-cylinders 5 and 5', through the ducts 12 12', the passages of the hollow connecting members 16 16', the

ducts 9 9' and 7 7' into the piston-chambers of said engine-cylinders to impart active movement to the pistons thereof, and to the engine-shaft through the intermediate connections between said pistons and the engine-shaft. As such pistons near the end of their active strokes the individual valve mechanisms of the aforesaid first and second engine-cylinders automatically reverse the positions of the ducts 9 10 and 9' 10', cutting off the communication of the pressure-supply ducts 9 9' with the interior of said cylinders and bringing the eduction-ducts 10 10' into communication therewith. As such positions of the described parts are reached in a cycle of the engine the motive fluid in each respective engine-cylinder is free to expand through the respective ducts 10 10' and the connecting-passages 22 22' into the storage-chamber 33 of the master-valve and into the secondary storage-chamber 31 when the same is employed, as heretofore described. From such storage or receiving chamber 33 of the master-valve the motive fluid passes to the third and fourth engine-cylinders 5" 5'" when the same reach their receiving position in a cycle of the engine, the motive fluid passing to the third engine-cylinder through the ducts or passages 40, 23", 12", 9", and 7" and to the fourth engine-cylinder through the ducts or passages 24, 12", 9", and 7". As the pistons of the respective cylinders 5" and 5'" near the end of their active stroke the individual valve mechanisms of said engine-cylinders automatically reverse the positions of the ducts 9" 9'" and 10" 10'", cutting off the communication of the pressure-supply ducts 9" and 9'" with the interior of said engine-cylinders and bringing the eduction-ducts 10" and 10'" into communication therewith, the motive fluid in which is free to exhaust in the case of the third engine-cylinder 5" through the passages or ducts 10" 13" 22" into the exhaust-chamber 32 of the master-valve and in the case of the fourth engine-cylinder 5'" through the passages or ducts 10'", 13", 24, and 27 into the exhaust-chamber 32 of the master-valve. From such exhaust-chamber 32 the motive fluid passes to the atmosphere or to a condenser through the exhaust-outlet passage 30 of the valve-chest of the master-valve.

Having thus fully described my said invention, what I claim as new, and desire to secure by Letters Patent, is—

55. 1. In a compound engine, the combination of a series of engine-cylinders, individual means for reversing the induction and education of the same, a master-valve controlling the induction and education ducts of said reversing means and adapted to couple the same for duplex or serial action, a valve-chest inclosing the master-valve, and means for adjusting the position of the master-valve, substantially as set forth.

65. 2. In a compound engine, the combination of a series of engine-cylinders, individual means for reversing the induction and education

of the same, a longitudinally-sliding master-valve controlling the induction and education ducts of said reversing means and adapted to couple the same for duplex or serial action, a valve-chest inclosing the master-valve, and means imparting longitudinal adjustment to the master-valve, substantially as set forth.

3. In a compound engine, the combination of a series of engine-cylinders, individual valves for reversing the induction and education of the same, a master-valve controlling the induction and education ducts of said reversing means and adapted to couple the same for duplex or serial action, a valve-chest inclosing the master-valve, and means for adjusting the position of the master-valve, substantially as set forth.

4. In a compound engine, the combination of a series of engine-cylinders, individual valves for reversing the induction and education of the same, a longitudinally-sliding master-valve controlling the induction and education ducts of said reversing means and adapted to couple the same for duplex or serial action, a valve-chest inclosing the master-valve, and means for imparting longitudinal adjustment to the master-valve, substantially as set forth.

5. In a compound engine, the combination of a series of engine-cylinders, individual means for reversing the induction and education of the same, a master-valve having a central longitudinal series of ducts and two series of marginal longitudinal ducts which are adapted to be alternately brought into action by the lateral adjustment of the master-valve, a valve-chest inclosing the master-valve, and means for imparting lateral adjustment to said valve, substantially as set forth.

6. In a compound engine, the combination of a series of engine-cylinders, individual means for reversing the induction and education of the same, a master-valve having a central longitudinal series of ducts and two series of marginal longitudinal ducts which are adapted to be alternately brought into action by the lateral adjustment of the master-valve, a valve-chest inclosing the master-valve, and means for imparting lateral adjustment to said valve, the same comprising a shaft journaled in the valve-chest and operative connections between the same and the master-valve, substantially as set forth.

7. In a compound engine, the combination of a series of engine-cylinders, individual means for reversing the induction and education of the same, a master-valve having a central longitudinal series of ducts and two series of marginal longitudinal ducts which are adapted to be alternately brought into action by the lateral adjustment of the master-valve and to couple the induction and education ducts of the individual reversing means for duplex or serial action by the longitudinal adjustment of the master-valve, a valve-chest inclosing the master-valve, and means for

imparting independent lateral and longitudinal movements to said valve, substantially as set forth.

8. In a compound engine, the combination of a series of engine-cylinders, individual means for reversing the induction and education of the same, a master-valve having a central longitudinal series of ducts and two series of marginal longitudinal ducts which are adapted to be alternately brought into action by the lateral adjustment of the master-valve, and to couple the induction and education ducts of the individual reversing means for duplex or serial action by the longitudinal adjustment of the master-valve, a valve-chest inclosing the master-valve, and means for imparting independent lateral and longitudinal movements to said valve, the same comprising a shaft capable of longitudinal and rotative movements and operative connections between the same and the valve, substantially as set forth.

9. In a compound engine, the combination of a series of engine-cylinders, individual means for reversing the induction and education of the same, a master-valve having a central longitudinal series of ducts and two series of marginal longitudinal ducts which are adapted to be alternately brought into action by the lateral adjustment of the master-valve, and to couple the induction and education ducts of the individual reversing means for duplex or serial action by the longitudinal adjustment of the master-valve, a valve-chest inclosing the master-valve, and means for imparting independent lateral and longitudinal movements to said valve, the same comprising a shaft capable of longitudinal and rotative movements, toothed sectors carried by said shaft, toothed racks secured to the valve and meshing with said sectors and abutment-pieces on the valve adapted to prevent independent longitudinal movement of said shaft, substantially as set forth.

10. In a compound engine, the combination of a series of engine-cylinders, individual means for reversing the induction and education of the same, a master-valve having a central longitudinal series of ducts and two series of marginal longitudinal ducts which are deflected laterally to meet at the middle of the master-valve and adapted to be alternately brought into action by the lateral adjustment of the master-valve, a valve-chest inclosing the master-valve, and means for imparting lateral adjustment to said master-valve, substantially as set forth.

11. In a compound engine, the combination of a series of engine-cylinders, individual means for reversing the induction and education of the same, a master-valve having a central longitudinal series of ducts and two series of marginal longitudinal ducts which are deflected laterally to meet at the middle of the master-valve and adapted to be alternately brought into action by the lateral adjustment of the master-valve, a valve-chest

inclosing the master-valve, and means for imparting lateral adjustment to said master-valve, the same comprising a shaft journaled in the valve-chest and operative connections between the same and the master-valve, substantially as set forth. 7c

12. In a compound engine, the combination of a series of engine-cylinders, individual means for reversing the induction and education of the same, a master-valve having a central longitudinal series of ducts and two series of marginal longitudinal ducts which are deflected laterally to meet at the middle of the master-valve and adapted to be alternately brought into action by the lateral adjustment of the master-valve, and to couple the induction and education ducts of the individual reversing means for duplex or serial action by the longitudinal adjustment of the master-valve, a valve-chest inclosing the master-valve, and means for imparting independent lateral and longitudinal movements to said valve, substantially as set forth. 8c

13. In a compound engine, the combination of a series of engine-cylinders, individual means for reversing the induction and education of the same, a master-valve having a central longitudinal series of ducts and two series of marginal longitudinal ducts which are deflected laterally to meet at the middle of the master-valve and adapted to be alternately brought into action by the lateral adjustment of the master-valve, and to couple the induction and education ducts of the individual reversing means for duplex or serial action by the longitudinal adjustment of the master-valve, a valve-chest inclosing the master-valve, and means for imparting independent lateral and longitudinal movements to said valve, substantially as set forth. 9c

14. In a compound engine, the combination of a series of engine-cylinders, individual means for reversing the induction and education of the same, a longitudinally-sliding master-valve controlling the induction and education ducts of said reversing means and adapted to couple the same for duplex or serial action, a valve-chest inclosing the master-valve, a storage-chamber controlled by the master-valve and adapted to receive the motive fluid from a forward engine-cylinder and store the same for reuse in a rearward engine-cylinder, and means for imparting longitudinal adjustment to the master-valve, substantially as set forth. 11c

15. In a compound engine, the combination of a series of engine-cylinders, individual means for reversing the induction and education of the same, a longitudinally-sliding master-valve controlling the induction and education ducts of said reversing means and adapted to couple the same for duplex or serial action, a valve-chest inclosing the master-valve, a storage-chamber formed in the master-

- valve and controlled by the movement of the same and adapted to receive the motive fluid from a forward engine-cylinder and store the same for reuse in a rearward engine-cylinder, 5 and means for imparting longitudinal adjustment to the master-valve, the same comprising a shaft journaled in the valve-chest and operative connections between the same and the master-valve, substantially as set forth.
- 10 16. In a compound engine, the combination of a series of single-acting engine-cylinders, individual means for reversing the induction and eduction of the same, a master-valve controlling the induction and eduction ducts of 15 said reversing means and adapted to couple the same for duplex or serial action, a valve-chest inclosing the master-valve, and means for adjusting the position of the master-valve, substantially as set forth.
- 15 17. In a compound engine, the combination of a series of single-acting engine-cylinders, individual means for reversing the induction and eduction of the same, a longitudinally-sliding master-valve controlling the induction and eduction ducts of said reversing 20 means and adapted to couple the same for duplex or serial action, a valve-chest inclosing the master-valve, and means imparting longitudinal adjustment to the master-valve, substantially as set forth.
- 25 18. In a compound engine, the combination of a series of single-acting engine-cylinders, individual valves for reversing the induction and eduction of the same, a master-valve controlling the induction and eduction ducts of 30 said reversing means and adapted to couple the same for duplex or serial action, a valve-chest inclosing the master-valve, and means for adjusting the position of the master-valve, substantially as set forth.
- 35 19. In a compound engine, the combination of a series of single-acting engine-cylinders, individual valves for reversing the induction and eduction of the same, a longitudinally-sliding master-valve controlling the induction and eduction ducts of said reversing 40 means and adapted to couple the same for duplex or serial action, a valve-chest inclosing the master-valve, and means for imparting longitudinal adjustment to the master-valve, substantially as set forth.
- 45 20. In a compound engine, the combination of a series of single-acting engine-cylinders, individual means for reversing the induction and eduction of the same, a master-valve having a central longitudinal series of ducts and 50 two series of marginal longitudinal ducts which are adapted to be alternately brought into action by the lateral adjustment of the master-valve, a valve-chest inclosing the master-valve, and means for imparting lateral adjustment to said valve substantially as set forth.
- 55 21. In a compound engine, the combination of a series of single-acting engine-cylinders, individual means for reversing the induction and eduction of the same, a master-valve having a central longitudinal series of ducts and 60 two series of marginal longitudinal ducts which are adapted to be alternately brought into action by the lateral adjustment of the master-valve, a valve-chest inclosing the master-valve, and means for imparting lateral adjustment to said valve substantially as set forth.
- 65 22. In a compound engine, the combination of a series of single-acting engine-cylinders, individual means for reversing the induction and eduction of the same, a master-valve having a central longitudinal series of ducts and 70 two series of marginal longitudinal ducts which are adapted to be brought into action by the lateral adjustment of the master-valve, a valve-chest inclosing the master-valve, and means for imparting lateral adjustment to said valve, the same comprising a shaft journaled in the valve-chest and operative connections between the same and the master-valve, substantially as set forth.
- 75 23. In a compound engine, the combination of a series of single-acting engine-cylinders, individual means for reversing the induction and eduction of the same, a master-valve having a central longitudinal series of ducts and 80 two series of marginal longitudinal ducts which are adapted to be alternately brought into action by the lateral adjustment of the master-valve, and to couple the induction and eduction ducts of the individual reversing means for duplex or serial action by the longitudinal adjustment of the master-valve, a valve-chest inclosing the master-valve, and 85 means for imparting independent lateral and longitudinal movements to said valve, substantially as set forth.
- 90 24. In a compound engine, the combination of a series of single-acting engine-cylinders, individual means for reversing the induction and eduction of the same, a master-valve having a central longitudinal series of ducts and 95 two series of marginal longitudinal ducts which are adapted to be alternately brought into action by the lateral adjustment of the master-valve, and to couple the induction and eduction ducts of the individual reversing means for duplex or serial action by the longitudinal adjustment of the master-valve, a valve-chest inclosing the master-valve, and 100 means for imparting independent lateral and longitudinal movements to said valve, the same comprising a shaft capable of longitudinal and rotative movements and operative 105 connections between the same and the valve, substantially as set forth.
- 110 25. In a compound engine, the combination of a series of single-acting engine-cylinders, individual means for reversing the induction and eduction of the same, a master-valve having a central longitudinal series of ducts and 115 two series of marginal longitudinal ducts which are adapted to be alternately brought into action by the lateral adjustment of the master-valve, and to couple the induction and eduction ducts of the individual reversing means for duplex or serial action by the longitudinal adjustment of the master-valve, a valve-chest inclosing the master-valve, and 120 means for imparting independent lateral and longitudinal movements to said valve, the same comprising a shaft capable of longitudinal and rotative movements, toothed sectors carried by said shaft, toothed racks secured to the valve and meshing with said 125 sectors and abutment-pieces on the valve.
- 130

adapted to prevent independent longitudinal movement of said shaft, substantially as set forth.

25. In a compound engine, the combination of a series of single-acting engine-cylinders, individual means for reversing the induction and eduction of the same, a master-valve having a central longitudinal series of ducts and two series of marginal longitudinal ducts 10 which are deflected laterally to meet at the middle of the master-valve and adapted to be alternately brought into action by the lateral adjustment of the master-valve, a valve-chest inclosing the master-valve, and means 15 for imparting lateral adjustment to said master-valve, substantially as set forth.

26. In a compound engine, the combination of a series of single-acting engine-cylinders, individual means for reversing the induction 20 and eduction of the same, a master-valve having a central longitudinal series of ducts and two series of marginal longitudinal ducts which are deflected laterally to meet at the middle of the master-valve and adapted to 25 be alternately brought into action by the lateral adjustment of the master-valve, a valve-chest inclosing the master-valve, and means for imparting lateral adjustment to said master-valve, the same comprising a shaft journaled 30 in the valve-chest and operative connections between the same and the master-valve, substantially as set forth.

27. In a compound engine, the combination of a series of single-acting engine-cylinders, 35 individual means for reversing the induction and eduction of the same, a master-valve having a central longitudinal series of ducts and two series of marginal longitudinal ducts which are deflected laterally to meet at the 40 middle of the master-valve and adapted to be alternately brought into action by the lateral adjustment of the master-valve, and to couple the induction and eduction ducts of the individual reversing means for duplex 45 or single action by the longitudinal adjustment of the master-valve, a valve-chest inclosing the master-valve, and means for imparting independent lateral and longitudinal movements to said valve, substantially as set 50 forth.

28. In a compound engine, the combination of a series of single-acting engine-cylinders, individual means for reversing the induction and eduction of the same, a master-valve 55 having a central longitudinal series of ducts and two series of marginal longitudinal ducts which are deflected laterally to meet at the middle of the master-valve and adapted to be alternately brought into action by the lateral 60 adjustment of the master-valve, and to couple the induction and eduction ducts of the individual reversing means for duplex or serial action by the longitudinal adjustment of the master-valve, a valve-chest inclosing 65 the master-valve, and means for imparting independent lateral and longitudinal movements to said valve, the same comprising

ing a shaft capable of longitudinal and rotative movements and operative connections between the same and the valve, substantially as set forth. 70

29. In a compound engine, the combination of a series of single-acting engine-cylinders, individual means for reversing the induction and eduction of the same, a longitudinally-sliding master-valve controlling the induction and eduction ducts of said reversing means and adapted to couple the same for duplex or serial action, a valve-chest inclosing the master-valve, a storage-chamber controlled 75 by the master-valve and adapted to receive the motive fluid from a forward engine-cylinder and store the same for reuse in a rearward engine-cylinder, and means for imparting longitudinal adjustment to the master-valve, substantially as set forth. 80

30. In a compound engine, the combination of a series of single-acting engine-cylinders, individual means for reversing the induction and eduction of the same, a longitudinally-sliding master-valve controlling the induction and eduction ducts of said reversing means and adapted to couple the same for duplex or serial action, a valve-chest inclosing the master-valve, a storage-chamber formed in 95 the master-valve and controlled by the movement of the same and adapted to receive the motive fluid from a forward engine-cylinder and store the same for reuse in a rearward engine-cylinder, and means for imparting 100 longitudinal adjustment to the master-valve the same comprising a shaft journaled in the valve-chest and operative connections between the same and the master-valve, substantially as set forth. 105

31. In a compound engine, the combination of a series of single-acting oscillating engine-cylinders, individual means for reversing the induction and eduction of the same, a master-valve controlling the induction and eduction 110 ducts of said reversing means and adapted to couple the same for duplex or serial action, a valve-chest inclosing the master-valve, and means for adjusting the position of the master-valve, substantially as set forth. 115

32. In a compound engine, the combination of a series of single-acting oscillating engine-cylinders, individual means for reversing the induction and eduction of the same, a longitudinally-sliding master-valve controlling 120 the induction and eduction ducts of said reversing means and adapted to couple the same for duplex or serial action, a valve-chest inclosing the master-valve, and means imparting longitudinal adjustment to the master-valve, substantially as set forth. 125

33. In a compound engine, the combination of a series of single-acting oscillating engine-cylinders, individual valves for reversing the induction and eduction of the same, a master-valve controlling the induction and eduction ducts of said reversing means and adapted to couple the same for duplex or serial action, 130 a valve-chest inclosing the master-valve, and

means for adjusting the position of the master-valve, substantially as set forth.

34. In a compound engine, the combination of a series of single-acting oscillating engine-cylinders, individual valves for reversing the induction and eduction of the same, a longitudinally-sliding master-valve controlling the induction and eduction ducts of said reversing means and adapted to couple the same for duplex or serial action, a valve-chest inclosing the master-valve, and means for imparting longitudinal adjustment to the master-valve, substantially as set forth.

35. In a compound engine, the combination of a series of single-acting oscillating engine-cylinders, individual means for reversing the induction and eduction of the same, a master-valve having a central longitudinal series of ducts and two series of marginal longitudinal ducts which are adapted to be alternately brought into action by the lateral adjustment of the master-valve, a valve-chest inclosing the master-valve, and means for imparting lateral adjustment to said valve, substantially as set forth.

36. In a compound engine, the combination of a series of single-acting oscillating engine-cylinders, individual means for reversing the induction and eduction of the same, a master-valve having a central longitudinal series of ducts and two series of marginal longitudinal ducts which are adapted to be alternately brought into action by the lateral adjustment of the master-valve, a valve-chest inclosing the master-valve, and means for imparting lateral adjustment to said valve, the same comprising a shaft journaled in the valve-chest and operative connections between the same and the master-valve, substantially as set forth.

37. In a compound engine, the combination of a series of single-acting oscillating engine-cylinders, individual means for reversing the induction and eduction of the same, a master-valve having a central longitudinal series of ducts and two series of marginal longitudinal ducts which are adapted to be alternately brought into action by the lateral adjustment of the master-valve and to couple the induction and eduction ducts of the individual reversing means for duplex or serial action by the longitudinal adjustment of the master-valve, a valve-chest inclosing the master-valve, and means for imparting independent lateral and longitudinal movements to said valve, substantially as set forth.

38. In a compound engine, the combination of a series of single-acting oscillating engine-cylinders, individual means for reversing the induction and eduction of the same, a master-valve having a central longitudinal series of ducts and two series of marginal longitudinal ducts which are adapted to be alternately brought into action by the lateral adjustment of the master-valve, and to couple the induction and eduction ducts of the individual reversing means for duplex or serial action by

the longitudinal adjustment of the master-valve, a valve-chest inclosing the master-valve, and means for imparting independent lateral and longitudinal movements to said valve, the same comprising a shaft capable of longitudinal and rotative movements and operative connections between the same and the valve, substantially as set forth.

39. In a compound engine, the combination of a series of single-acting oscillating engine-cylinders, individual means for reversing the induction and eduction of the same, a master-valve having a central longitudinal series of ducts and two series of marginal longitudinal ducts which are adapted to be alternately brought into action by the lateral adjustment of the master-valve, and to couple the induction and eduction ducts of the individual reversing means for duplex or serial action by the longitudinal adjustment of the master-valve, a valve-chest inclosing the master-valve, and means for imparting independent lateral and longitudinal movements to said valve, the same comprising a shaft capable of longitudinal and rotative movements, toothed sectors carried by said shaft, toothed racks secured to the valve and meshing with said sectors and abutment-pieces on the valve adapted to prevent independent longitudinal movement of said shaft, substantially as set forth.

40. In a compound engine, the combination of a series of single-acting oscillating engine-cylinders, individual means for reversing the induction and eduction of the same, a master-valve having a central longitudinal series of ducts and two series of marginal longitudinal ducts which are deflected laterally to meet at the middle of the master-valve and adapted to be alternately brought into action by the lateral adjustment of the master-valve, a valve-chest inclosing the master-valve, and means for imparting lateral adjustment to said master-valve, substantially as set forth.

41. In a compound engine, the combination of a series of single-acting oscillating engine-cylinders, individual means for reversing the induction and eduction of the same, a master-valve having a central longitudinal series of ducts and two series of marginal longitudinal ducts which are deflected laterally to meet at the middle of the master-valve and adapted to be alternately brought into action by the lateral adjustment of the master-valve, a valve-chest inclosing the master-valve, and means for imparting lateral adjustment to said master-valve, the same comprising a shaft journaled in the valve-chest and operative connections between the same and the master-valve, substantially as set forth.

42. In a compound engine, the combination of a series of single-acting oscillating engine-cylinders, individual means for reversing the induction and eduction of the same, a master-valve having a central longitudinal series of ducts and two series of marginal longitudinal ducts which are deflected laterally to meet

at the middle of the master-valve and adapted to be alternately brought into action by the lateral adjustment of the master-valve, a valve-chest inclosing the master-valve, and to couple the induction and eduction ducts of the individual reversing means for duplex or serial action by the longitudinal adjustment of the master-valve, and means for imparting independent lateral and longitudinal movements to said valve, substantially as set forth.

43. In a compound engine, the combination of a series of single-acting oscillating engine-cylinders, individual means for reversing the induction and eduction of the same, a master-valve having a central longitudinal series of ducts and two series of marginal longitudinal ducts which are deflected laterally to meet at the middle of the master-valve and adapted to be alternately brought into action by the lateral adjustment of the master-valve, and to couple the induction and eduction ducts of the individual reversing means for duplex or serial action by the longitudinal adjustment of the master-valve, a valve-chest inclosing the master-valve, and means for imparting independent lateral and longitudinal movements to said valve, the same comprising a shaft capable of longitudinal and rotative movements and operative connections between the same and the valve, substantially as set forth.

44. In a compound engine, the combination of a series of single-acting oscillating engine-cylinders, individual means for reversing the induction and eduction of the same, a longitudinally-sliding master valve controlling the induction and eduction ducts of said reversing means and adapted to couple the same for duplex or serial action, a valve-chest inclosing the master-valve, a storage-chamber controlled by the master-valve and adapted to receive the motive fluid from a forward engine-cylinder and store the same for reuse in a rearward engine-cylinder, and means for imparting longitudinal adjustment to the master-valve, substantially as set forth.

45. In a compound engine, the combination of a series of single-acting oscillating engine-cylinders, individual means for reversing the induction and eduction of the same, a longitudinally-sliding master-valve controlling the induction and eduction ducts of said reversing means and adapted to couple the same for duplex or serial action, a valve-chest inclosing the master-valve, a storage-chamber formed in the master-valve and controlled by the movement of the same and adapted to receive the motive fluid from a forward engine-cylinder and store the same for reuse in a rearward engine-cylinder, and means for imparting longitudinal adjustment to the master-valve, the same comprising a shaft journaled in the valve-chest and operative connections between the same and the master-valve, substantially as set forth.

46. In a single-acting oscillating engine of

the character herein described, the combination of an engine-cylinder, an end-closure head for the same formed with a segmental face or seat and provided with a central induction-eduction duct to constitute the oscillating member of the engine-reversing valve, a non-oscillating valve member formed with spirally-arranged induction and eduction ducts adapted to alternately register with the induction-eduction duct of the cylinder, a fluid-supply chest, means for flexibly connecting the induction-duct of the non-oscillating valve member with the fluid-supply chest of the engine, and a yielding connection holding the non-oscillating valve member to its seat against the pressure of the motive-fluid supply, substantially as set forth.

47. In a single-acting oscillating engine of the character herein described, the combination of an engine-cylinder, an end-closure head for the same formed with a segmental face or seat and provided with a central induction-eduction duct to constitute the oscillating member of the engine-reversing valve, a non-oscillating valve member formed with spirally-arranged induction and eduction ducts adapted to alternately register with the induction-eduction duct of the cylinder, a fluid-supply chest, a fluid-discharge chest, flexible connections between said induction and eduction ducts of the non-oscillating valve member and the supply and discharge chests of the engine, and means for holding the non-oscillating valve member to its seat in a yielding manner, substantially as set forth.

48. In a single-acting oscillating engine of the character herein described, the combination of an engine-cylinder, an end-closure head for the same formed with a segmental face or seat and provided with a central induction-eduction duct to constitute the oscillating member of the engine-reversing valve, a non-oscillating valve member formed with spirally-arranged induction and eduction ducts adapted to alternately register with the induction-eduction duct of the cylinder, a fluid-supply chest, a flexible bar or member attached at one end of the engine-frame and having an intermediate bearing upon the non-oscillating valve member, an adjusting-bolt connected to the engine-frame and to the other end of said bar or member and adapted to regulate the tension of the same, and means for flexibly connecting the induction-duct of the non-oscillating valve member with the fluid-supply chest of the engine, substantially as set forth.

49. In a single-acting oscillating engine of the character herein described, the combination of an engine-cylinder, an end-closure head for the same formed with a segmental face or seat and provided with a central induction-eduction duct to constitute the oscillating member of the engine-reversing valve, a non-oscillating valve member formed with spirally-arranged induction and eduction ducts adapted to alternately register with the in-

duction-eduction duct of the cylinder, a fluid-supply chest, a fluid-discharge chest, flexible connections between said induction and eduction ducts of the non-oscillating valve member and the supply and discharge chests of the engine, a flexible bar or member attached at one end to the engine-frame and having intermediate bearing upon the non-oscillating valve member, and an adjusting-bolt connected to the engine-frame and to the other end of said bar or member and adapted to regulate the tension of the same, substantially as set forth.

50. In a single-acting oscillating engine of the character herein described, the combination of an engine-cylinder, an end-closure head for the same formed with a segmental face or seat and provided with a central induction-eduction duct to constitute the oscillating member of the engine-reversing valve, a non-oscillating valve member formed with spirally-arranged induction and eduction ducts adapted to alternately register with the induction-eduction duct of the cylinder, a fluid-supply chest, a hollow intermediate member pivotally connected to the supply-chest of the engine and to the non-oscillating valve member to constitute a flexible conducting connection between the parts, and a yielding connection holding the non-oscillating valve member to its seat, substantially as set forth.

51. In a single-acting oscillating engine of the character herein described, the combination of an engine-cylinder, an end-closure head for the same formed with a segmental face or seat and provided with a central induction-eduction duct to constitute the oscillating member of the engine-reversing valve, a non-oscillating valve member formed with spirally-arranged induction and eduction ducts adapted to alternately register with the induction-eduction duct of the cylinder, a fluid-supply chest, a fluid-discharge chest, a pair of hollow intermediate members pivotally connected to the supply and discharge chests of the engine and to the non-oscillating valve member to constitute flexible conducting connections between the parts, and a yielding connection holding the non-oscillating valve member to its seat, substantially as set forth.

52. In a single-acting oscillating engine of the character herein described, the combination of an engine-cylinder, an end-closure head for the same formed with a segmental face or seat and provided with a central induction-eduction duct to constitute the oscillating member of the engine-reversing valve, a non-oscillating valve member formed with spirally-arranged induction and eduction ducts adapted to alternately register with the induction-eduction duct of the cylinder, a fluid-supply chest, a fluid-discharge chest, a pair of hollow intermediate members pivotally connected to the supply and discharge chests of the engine, and to the non-oscillating valve member to constitute flexible conducting connections between the parts, a centrally-ar-

ranged tie-bolt connecting the intermediate members together, and a yielding connection holding the non-oscillating valve member to its seat, substantially as set forth.

53. In a single-acting oscillating engine of the character herein described, the combination of an engine-cylinder, an end-closure head for the same formed with a segmental face or seat and provided with a central induction-eduction duct to constitute the oscillating member of the engine-reversing valve, a non-oscillating valve member formed with spirally-arranged induction and eduction ducts adapted to alternately register with the induction-eduction duct of the cylinder, a fluid-supply chest, a fluid-discharge chest, a pair of hollow intermediate members pivotally connected to the supply and discharge chests of the engine and to the non-oscillating valve member to constitute flexible conducting connections between the parts, a centrally-arranged tie-bolt connecting the intermediate members together, an elastic piece inserted between the bolt-head and one of the members, and a yielding connection holding the non-oscillating valve member to its seat, substantially as set forth.

54. In a single-acting oscillating engine of the character herein described, the combination of an engine-cylinder, an end-closure head for the same formed with a segmental face or seat and provided with a central induction-eduction duct to constitute the oscillating member of the engine-reversing valve, a non-oscillating valve member formed with spirally-arranged induction and eduction ducts adapted to alternately register with the induction-eduction duct of the cylinder, a fluid-supply chest, a hollow intermediate member formed with tubular necks by which it is pivotally connected to the supply-chest of the engine and to the non-oscillating valve member to constitute a flexible conducting connection between the parts, and a yielding connection holding the non-oscillating valve member to its seat, substantially as set forth.

55. In a single-acting oscillating engine of the character herein described, the combination of an engine-cylinder, an end-closure head for the same formed with a segmental face or seat and provided with a central induction-eduction duct to constitute the oscillating member of the engine-reversing valve, a non-oscillating valve member formed with spirally-arranged induction and eduction ducts adapted to alternately register with the induction-eduction duct of the cylinder, a fluid-supply chest, a fluid-discharge chest, a pair of hollow intermediate members formed with tubular necks by which they are pivotally connected to the supply and discharge chests of the engine and to the non-oscillating valve member to constitute flexible conducting connections between the parts, and a yielding connection holding the non-oscillating valve member to its seat, substantially as set forth.

56. In a single-acting oscillating engine of the character herein described, the combination of a single-acting engine-cylinder provided with a central induction-eduction duct, 5 a valve member controlling said duct, a fluid-supply chest, a piston fitting said cylinder, and having an annular form open at one end and closed at the other end by a head, a pitman attached centrally to the closure-head of the piston, and a spider forming an intermediate connection between the pitman and the annular portion of the piston, substantially as set forth.

57. In a single-acting oscillating engine of the character herein described, the combination of a single-acting engine-cylinder provided with a central induction-eduction duct, 15

a valve member controlling said duct, a fluid-supply chest, a piston fitting said cylinder, and having an annular form open at one end and closed at the other end by a head, a pitman attached centrally to the closure-head of the piston, and a spider forming an intermediate connection between the pitman and the annular portion of the piston, the piston, pitman and spider being integrally formed, substantially as set forth. 20

Signed at Chicago, Illinois, this 15th day of October, 1901.
